MAGNETRON TELEGRAPHIC REPEATER

Louis M. Potts, Evanston, Ill., assignor to Teletype Corporation, Chicago, Ill., a corporation of Delaware

Application December 20, 1937, Serial No. 180,717

12 Claims. (Cl. 178—71)

This invention pertains to telegraphic systems and apparatus and more particularly to such systems in which the distance between terminal stations renders necessary the provision of an intermediate station equipment with telegraphic repeating devices to renew the strength of the signal impulses.

The invention pertains more particularly to systems which serve a large traffic at a high speed of transmission in which the time required for the operation of mechanical armatures of magnetic relays becomes a restraining feature in the speed of operation of the system, particularly from the viewpoint of repeating the impulses at a repeater station where transit time of an armature in a mechanical electromagnetic relay introduces a degree of distortion into the time dimension of repeated impulses.

Accordingly, the present invention has as its principal object the provision of repeating equipment wholly independent of any mechanically movable elements.

Features of the invention are embodied in an improved substation equipment and in details of elements of the assembled system and in variations of the preferred form of the invention.

The invention is illustrated in its preferred form; namely, an arrangement to provide circuits including a symmetrical assembly of electronic devices to effect two-way single-line transmission through a repeating station with suppression of echo signals by means wholly independent of any mechanical operating member. Transmission also is effected through a repeating station by reversed signals or open-circuit principles, and signal impulses are reversed at a terminal station to operate a recorder of closed circuit type.

For illustration of the invention, the drawings show a magnetron, comprising a tubular anode surrounding an axial cathode and surrounded by helical windings. When the cathode is heated and potential is applied from cathode to anode without current in any winding, the electronic path from cathode to anode, called "plate circuit," is in conducting condition. When a magnetic field of sufficient strength is produced by current in either polar sense in the windings, the plate circuit of a magnetron becomes non-conducting. An effective magnetic field may be produced by a controlling current through a single winding in a magnetron, or a biasing current in one winding may produce a magnetic field which, when increased by a small controlling current in another winding, may render the plate circuit

non-conducting, or alternatively a biasing current in one winding may render the plate circuit non-conducting by a strong magnetic field which, when decreased by a small opposing controlling current in another winding, may render the plate circuit conducting.

In the systems of the present invention, a plurality of magnetrons are associated by circuits to form a single-line two-way repeating system, and magnetic fields are combined differentially or cumulatively in the several magnetrons to effect suppression of reflection signals.

A better understanding of the invention may be had from the following description taken in conjunction with the accompanying drawing 15

Fig. 1 illustrates circuits and apparatus of a system including two substations and a repeating station operating upon closed circuit principles of telegraph transmission with echo suppression according to this invention:

Fig. 2 illustrates a modification thereof operating upon open-circuit principles with arrangement for echo suppression;

Fig. 3 illustrates a modification of the structure of Fig. 1; and,

Fig. 4 illustrates a substation equipment for open circuit working.

Referring to the drawing for a detailed description, Fig. 1 illustrates a two-way magnetron repeating system between two line sections, having four magnetron tubes in which one tube is used for controlling transmission currents and one tube is used for controlling echo suppression currents in response to signals received from each of the two line sections. Tubes 1, 2, 3, and 4 have line windings 5, 6, 7, and 8 and biasing windings 9, 10, 11, 12, respectively. Local currents in echo suppression windings 13 and 15 are controlled by plate circuit 18 of tube 4, and currents in echo suppression windings 14 and 16 are controlled by plate circuit 17 of tube 3. Currents in the line windings are supplied from batteries 19 and 20 through resistors 21, 22 and plate circuits 23, 24, of tubes 1 and 2, thence flowing through windings 5, 6, 7, 8 in that polar sense indicated by arrows, and thence over line sections 25, 26 and through transmitters and receivers (not shown) in substations 27, 28, respectively, and to ground.

In transmitting tubes 1 and 2, the biasing currents in windings 9 and 10 oppose the line currents in magnetic effect, the difference or remaining magnetic field being too weak to render either tube non-conducting, but the biasing current being sufficient to render either tube 1 or 2 non- 55

conducting when unopposed by either line or local current.

In tube 4, biasing current in winding 12 is ineffective to render the tube non-conducting but 5 the tube 4 is non-conducting when current also is flowing in winding 8 or in winding 16. Tube 3 operates similarly.

For purposes of description, it will be assumed 10 that a start-stop printing telegraph unit is used, such as described in U. S. Patent 1,904,164 issued to Morton et al., but the repeater is equally well adapted to many other types of telegraph machines.

In operation, tubes 1 and 2 are conducting 15 while tubes 3 and 4 are non-conducting, for a marking signal.

Upon operation of the transmitter (not shown) 20 in substation 27 for a spacing signal, current is interrupted in line 28 and in line windings 6 and 7, permitting magnetron 3 to render its plate circuit 17 conducting, and causing magnetron 1 to render its plate circuit 23 non-conducting. The non-conducting condition of plate circuit 23 25 interrupts current in line 26 and in line windings 6 and 8, while the conducting condition of plate circuit 17 establishes current in local windings 14 and 16, replacing magnetic effects of current discontinued from line windings 6 and 8 and effecting echo suppression in both tubes 2 and 4. 30 Upon reclosing the line 25 at substation 27 to reestablish the original signaling condition of marking nature, current will flow from battery 20, through resistor 22 and conducting plate circuit 24 of magnetron 2, through line windings 35 5 and 7, line 25, and substation 27 to ground. Magnetrons 1 and 3 will return to conducting and non-conducting conditions respectively, current in windings 14 and 16 will be discontinued, and current in line 26 and line windings 6 and 8 40 will be restored.

A modification is illustrated in Fig. 2 in which but two magnetrons are used. Each magnetron 71, 72 is provided with a local winding 73, 74, a receiving line winding 75, 76, and a retransmitting line winding 77, 78. Each receiving circuit 45 includes a thermo-electronic valve 79, 80. Two substations 81, 82 are shown connected through line conductors 83, 84 to grids 85, 86, respectively, and branching through windings 77, 78, respectively, to plate circuits of magnetrons 72, 71, 50 respectively, and through resistors 88, 87 to battery connections. Local circuits for received signals include cathodes 89, 90, plates 91, 92, windings 75, 76, portions of potentiometer resistors 93, 94, 55 and contactors 95, 96. At substation 81, the line conductor 83 is connected through a neutral relay 101 and a resistor 103 to a ground connection, to complete a line circuit for received signals, which is supplemented by a local circuit 60 for received signals including a battery 105, recorder selector magnet 107, and a back contact and armature of deenergized line relay 101. There is provided also a transmitting equipment 65 including battery 109, a resistor 111, a transmitting armature 113 and back contact, which has the function of applying the potential of battery 109 to the line conductor 83 for signaling effect in response to control by a permutation transmitter 130.

70 Currents in polarizing windings 73, 74 are only sufficient to energize the magnetrons 71, 72 to render their plate circuits non-conducting, the current from valves 79, 80 through windings 75, 76, when flowing in response to a received signal 75 of spacing nature, are opposed to the currents

in magnetic effect and are sufficient in intensity to reduce the energization of the respective tubes to a degree permitting the plate circuits to become conducting when no current is flowing in winding 77 or 78, respectively, but insufficient to render the plate circuits conducting against the joint magnetic effect of currents in windings 73, 77 or windings 74, 78.

The structure of Fig. 2 is illustrated in condition of a continuous marking signal as indicated 10 by the energized condition of the recording magnets 107, 108 at the substations 81, 82, with the contacts of transmitter 113 open, with the marking condition of no current upon the line conductors 83, 84, no currents in windings 75, 76, 15 77, 78, and with currents as described above in local windings 73, 74, rendering magnetrons 71 and 72 non-conducting.

A spacing signal is effected in the system by 20 opening the contacts of transmitter 130 to de-energize the relay 113 which energizes line relay 101 and grid 85, but which produces no current in winding 77 because of the non-conducting condition of the plate circuit of tube 72. Relay 101 operates its armature and produces a spacing signal in the home recorder 107. Grid 85 renders the plate circuit of valve 79 conducting thereby establishing current in winding 75 and rendering the plate circuit of tube 71 conducting to establish current in winding 78 of tube 72 30 and relay 102 in substation 82, and also polarizing the grid 86 in valve 80. Current in winding 78 increases the magnetic field in tube 72. Energization of relay 102 operates its armature and produces a repeated spacing signal in the 35 remote recorder 108 and polarization of grid 86 renders the valve 80 conducting and establishes a current in winding 76. Since the current in winding 78 was established before the opposing current in winding 76, the plate circuit of the 40 magnetron 72 has been held non-conducting through the described operation.

To reestablish the marking condition in the system, contact of transmitter 130 is closed, re-energizing the relay 113, interrupting current in 45 relay 101, which reestablishes marking conditions in home recorder 107, and interrupting also polarization of grid 86 which interrupts current in winding 75 and restores the plate circuit of magnetron 71 to non-conducting condition to interrupt current in line relay 102 which releases its armature and effects a repeated marking signal in remote recorder 108. Magnetron 71, in resuming its non-conducting plate circuit condition, depolarizes the grid 86 and in- 50 terrupts current in winding 78. Interruption of current in winding 78 leaves magnetron 72 to the combined influence of currents in windings 74 and 76, which is a condition to render the plate circuit of the magnetron conducting but 55 depolarization of the grid 86 at this time renders valve 80 non-conducting and immediately thereafter interrupts the current in winding 76 to restore magnetron 72 to its normal magnetic condition with a non-conducting plate circuit. 60

With reference to Fig. 3, two line sections 57, 58 are shown connecting two substations 59, 60 to a central office equipment wherein line section 57 is connected to magnetrons 42, 43 and line section 58 is connected to magnetrons 41, 70 44. Biasing windings are indicated at 49, 50, 51, 52. A line signaling circuit extends from grounded battery through resistor 54, plate circuit of magnetron 42, winding 55 of magnetron 43, line section 57, and substation 59 to ground. 75

A companion line circuit extends from grounded battery through resistor 53, plate circuit of magnetron 41, winding 56 of magnetron 44, line 58 and substation 60 to ground. Local circuit under control of signals in line circuit 57 extends from grounded battery through resistor 62, winding 64 of magnetron 44, winding 47 of magnetron 41 and plate circuit of magnetron 43 to ground, the winding 47 being shunted by a condenser 45. 10 This circuit is open by virtue of non-conducting plate circuits in magnetron 43 when the signal in line section 57 is a marking signal.

With a marking signal in the two line sections 57, 58, the two magnetrons 41, 42 are biased only by current in windings 49, 50, and their plate circuits are conducting while the two magnetrons 43, 44 each biased by magnetism of its biasing windings 51 or 52 and supplemented by magnetism of its line windings 55, 56, are both 20 non-conducting.

Beginning of current in the described local circuit has first the effect of producing a magnetic field in magnetron 44, simultaneously charging the condenser 45, and subsequently producing a magnetic field in magnetron 41 after a delay due to the presence of condenser 45, which acts as a by-pass for the initial moment of current flow in the described local circuit.

In operation the beginning of a spacing signal at substation 59 will open the described line circuit, thus decreasing the magnetization of magnetron 43 and causing its plate circuit to become conducting, thus starting current in the described local circuit and increasing the magnetization of magnetron 44 to continue the non-conducting condition of its plate circuit after which current in winding 47 of the local circuit increases magnetization of magnetron 41 and renders its plate circuit non-conducting, thus 40 opening the circuit of the line section 58 and repeating into substation 50 the spacing signal originated in substation 59. At the cessation of current in line section 58 no effect is produced in magnetron 44 since the magnetism of winding 64 replaces the magnetism of winding 56 and jointly with the magnetism of biasing winding 52 maintains the magnetron 44 in non-conducting condition, thus estopping echo signals.

Upon reclosing the circuit of substation 59 to begin the ensuing marking signal, current flows again through winding 55 rendering the plate circuit of magnetron 43 non-conducting and preserving the plate circuit of magnetron 44 conducting, followed immediately by cessation of current in winding 47, thus rendering magnetron 41 conducting and restoring current in line section 58, repeating in substation 60 the marking signal generated in substation 59. Transmission in reverse order from substation 59 is obvious. Any 50 current impulse in the local circuit from grounded battery through resistor 61, winding 63, winding 48, and plate circuit of magnetron 44 which may occur during the period of discharge of condenser 45 is so brief that it is negligible and 60 ineffective upon either substation 59 or 60.

A substation equipment is illustrated in Fig. 4 wherein is shown an assembly operating under the conditions explained above for substation 81, Fig. 2. A thermo-electronic valve 120 has its grid 121 connected to line conductor 122 and its plate circuit connected through winding 123 of recorder magnet 124 which is electro-polarized by its winding 125 over an obvious circuit. A transmitter, when operated to open its contacts, deenergizes a relay whose contact 126, when re-

leased, connects battery 127 through resistor 128 to line conductor 122. The structure of Fig. 4 is illustrated in its normal condition of a marking signal as evidenced by the attracted positions of the armature 129 of recorder magnet 5 124 and contact 126 of the transmitter relay. In this condition, the line conductor 122 is without potential, the grid 121 is at ground potential, no current flows in winding 123, and polarizing current in winding 125 is sufficient to cause the 10 recorder magnet 124 to hold its armature 129 after return of the armature 129 to the pole of the magnet 124 by mechanical action of a cam (not shown). Upon receipt of a signal of spacing nature upon grid 121, either from the home 15 transmitter contact 126 or over the line conductor 122, current will flow in the plate circuit of valve 120 and in winding 123, decreasing the electromagnetic field produced by uniform current in winding 125 and releasing the armature 129 to 20 effect a signal of spacing nature in the recorder.

The magnet 124 is illustrated as a holding magnet, described in detail in connection with a permutation code recorder in Patent No. 1,904,164 issued to S. Morton et al. The magnet 124 may 25 be of any type and may control any type of printer. The cam (not shown) for assisting the operation of the armature 129 is fully described in Patent No. 1,917,308 issued to H. L. Krum, in which patent will be found the details of operation of mechanically assisted armature 129. 30

The invention has been described in connection with specific illustrative systems which are capable of modification without departing from the spirit or scope of the invention, the invention being limited only by the scope of the appended claims.

What is claimed is:

1. In a telegraph two-way single-line repeating system, two line sections, each said section operating alternatively as a line circuit for received signals or as a line circuit for retransmitted signals, two pairs of signal responsive magnetron valves, one of said pairs having windings for incoming signals included in a circuit with one of said line sections, the space discharge gap of one valve of said one pair being included in a circuit with the other of said line sections for retransmission signals, and the space discharge gap of the other valve of said one pair being included 45 in an echo-suppression circuit.

2. In a telegraph two-way single-line repeating system, two line sections, each said section operating alternatively as a line circuit for received signals or as a line circuit for retransmitted signals, two pairs of signal responsive magnetron valves, one pair having signal receiving windings included in a circuit with one of said line sections, a space discharge gap of one valve of said one pair being included in a retransmission circuit with the other of said line sections for generating retransmission signals in response to received signals, and the space discharge gap of the other valve of said one pair being included in a circuit including also windings of each of the valves of the other pair of said signal responsive magnetron valves whereby said other pair of valves are rendered non-responsive.

3. In a telegraph two-way single-line repeating system, two associated magnetrons simultaneously 70 responsive to received signals, a normally closed space discharge gap in one of said magnetrons which opens responsively to a received changed signal, a normally open space discharge gap in the other of said magnetrons which closes respons- 75

- sively to a received changed signal, a retransmission conductor having a normally continuous signal current included in circuit with said normally closed space discharge gap, and echo-suppression means included in a normally currentless circuit with said normally open space discharge gap, whereby upon receipt of a changed signal said normally currentless circuit will be closed by said normally open plate space gap and will be supplied with current for rendering said echo-suppression means effective.
4. In a telegraph two-way single-line repeating system, two associated magnetrons simultaneously responsive to received signals, a normally closed plate circuit in one of said magnetrons, a normally open plate circuit in the other of said magnetrons, a retransmission conductor included in circuit with said normally closed plate circuit, and echo-suppression means additional to said two magnetrons and included in said normally open plate circuit of said other of said two magnetrons.
5. In a telegraph two-way single-line repeating system, two associated magnetrons simultaneously responsive to received signals, a retransmission conductor included in the plate circuit of one of said magnetrons, and echo-suppression means additional to said two magnetrons and included in the plate circuit of the other of said magnetrons.
- 30 6. In a telegraph two-way single-line repeating system, two line sections, two associated magnetrons having respectively normally conducting and normally non-conducting space discharge paths and responsive to signals from one of said line sections, means controlled by one of said magnetrons to repeat the received signals over the other of said line sections, and means controlled by the other of said magnetrons to effect estoppel of reflection signals.
- 40 7. In a telegraph two-way single-line repeating system, two line sections, a quick-to-operate magnetron and a slow-to-operate magnetron both responsive to signals from one of said line sections, means controlled by said slow-to-operate magnetron to repeat the received signals over the other of said line sections, and means controlled by said quick-to-operate magnetron to effect estoppel of reflection signals.
- 45 8. In a telegraph two-way single-line repeating system, two line sections, two signal responsive magnetrons normally in space conducting condition controlled over said line sections respectively, two further signal responsive magnetrons normally in space non-conducting condition controlled over said line sections respectively, and repeating circuits for said magnetrons each repeating circuit including a space path in one of said magnetrons, a winding in one of said further magnetrons and one of said line sections.
9. In a telegraph two-way, single channel repeating system, two line sections, two magnetrons responsive to signals received over said line sections respectively, polarizing windings in said magnetrons, said windings being energized continuously and effective when unopposed to render said magnetrons nonconductive, and two line circuits normally carrying current, each circuit including one of said line sections, the plate circuit of one of said magnetrons and a winding of the other magnetron, said winding being effective when energized by the line current to oppose the polarizing winding and render said other magnetron conductive.
10. In a telegraph two-way single-channel repeating system, two line sections, two signal repeating magnetrons connected in retransmitting manner by electromagnetic coupling between said two line sections, and means responsive directly to received signals to estop reflection signals.
- 15 11. In a telegraph two-way single-line repeating system, two line sections, two magnetrons having windings controlled by one of said line sections and responsive to signals received from said line section, a condenser connected as a shunt with one of said windings, one of said magnetrons being operative to repeat the received signals, and the other of said magnetrons being operative to effect estoppel of reflection signals.
- 20 12. In a telegraph two-way single-line repeating system, two line section circuits, each circuit operating alternatively as a line circuit for received signals or as a line circuit for retransmitted signals, two space-discharge devices, one for each of said circuits, the space-discharge path of the device being included as a part of the circuit, first means for maintaining either of said space-discharge paths in conductive condition in one of said circuits during periods of marking signals in the other of said circuits, and second means for maintaining one only of said space-discharge paths in conductive condition in one of said circuits during periods of concurrent spacing signals in both of said circuits.

LOUIS M. POTTS.
